COUNTER DISPLAY CARD

Arnold H. Kossoff, 67 Metropolitan Ave., Brooklyn, N.Y.

Filed Mar. 16, 1964, Ser. No. 79,006

Term of patent 14 years

(Cl. D80—9)

FIG. 2

FIG. 5

FIG. 1

FIG. 3

FIG. 4

I claim:

The ornamental design for a counter display card, substantially as shown and described.
